UNITED STATES PATENT OFFICE.

MOSES EWING, OF CHESTER, PENNSYLVANIA, ASSIGNOR OF ONE-HALF TO CHARLES
LESLIE GILLILAND, OF CHESTER, PENNSYLVANIA.

SLUB-CATCHER.

1,102,213.

Specification of Letters Patent. Patented June 30, 1914.

Application filed April 1, 1913. Serial No. 758,165.

To all whom it may concern:

Be it known that I, MOSES EWING, a citizen of the United States, residing at Chester, in the county of Delaware and State of Pennsylvania, have invented certain new and useful Improvements in Slub-Catchers, of which the following is a specification.

My invention relates to improvements in slub catchers, and more particularly to an improved slub catching attachment for cone winders, the object of the invention being to provide an efficient slub catcher which will clear the thread, preventing lumps or slubs from passing to the cone and causing the thread to break before permitting a slub or lump to pass.

A further object is to provide a slub catcher comprising two brushes supported at the ends of lazy tongs which are supported in such a manner that when the thread breaks, the brushes will separate and the cone be elevated out of contact with its friction driving roll.

With these and other objects in view, the invention consists in certain novel features of construction and combinations and arrangements of parts as will be more fully hereinafter described and pointed out in the claims.

30 In the accompanying drawings: Figure 1 is a view partly in section and partly in side elevation illustrating my improvements in normal operative position. Fig. 2 is a plan view of the slug catcher *per se*. Fig. 3 is a view similar to Fig. 1 showing the position of the parts when the thread breaks. Fig. 4 is a perspective view of one of the brushes. Fig. 5 is a view in cross section on the line 5—5 of Fig. 2. Fig. 6 is a view in front elevation with the parts as shown in Fig. 1, and Fig. 7 is a perspective view of the wire frame supporting bracket.

My improvements are used in connection with a cone winding machine, and I have illustrated in connection with my improvements, only such portions of the machine as are necessary to illustrate the carrying out of my invention.

1 is a horizontal bar constituting a fixed 50 or stationary part of the machine frame having brackets 2 secured thereon and supporting a shaft 3 containing a roll 4 which is adapted to frictionally turn a cone 5 when the latter rests thereon. This cone 5 is supported by a rotary holder 6 secured to one

member 7 of a bell-crank-lever 8 which is pivotally supported on a rod 9 mounted in extensions 10 on brackets 2.

The brackets 2 are made with bearings 11 to receive arbors 12 secured in sleeves 13 on a plate 14, and afford pivotal mounting for this plate. Plate 14 is made with posts 15 at its upper end in which a wire guide 16 is secured and over this guide 16, the thread to be wound on the cone is passed, and is directed onto the cone by a guide 17^a mounted to slide on a bar 18 and operated by a cam 19, a fragment of the latter being illustrated.

On the lower end of plate 14, a relatively long arm 20 and a relatively short arm 21 are cast integral with the plate and support a rod 22. A catch 23 is pivotally supported between its ends on the rod 22, and is normally held in an elevated position by a wire frame 24 which is supported in a bracket 25 secured to the plate 14. This wire frame 24 at one end has a crank arm 26 which bears against the shorter end 27 of catch 23, while the opposite end of this wire frame constitutes a horizontal guide 28 under which the 80 cord 17 is positioned and maintained elevated by the cord.

As soon as the cord breaks, the frame 28 will fall and permit the catch 23 to fall to the position shown in dotted lines in Fig. 1 85 into the path of movement of an oscillating trip 29, continuously oscillating with a shaft 30. When the catch falls to this position, the downward oscillating movement of the part 29 will turn the plate downwardly upon 90 its arbors 12 to the position shown in Fig. 3.

The plate is held in its normal operative position by a spring 31 secured on bar 1, and having a curved recess 32 in its free end, which receives a rotary sleeve 33 on a pin 95 34 fixed in integral ears 35 on the bottom of plate 14. When the plate is pulled downwardly by the oscillator 29, the sleeve 33 will be drawn rearwardly out of the recess 32, and lie in the position shown in Fig. 3. 100 When again elevated, the recessed end 32 will spring upwardly and hold the parts in normal position as will be readily understood.

A frame 36 is pivotally mounted on the rod 22, and is formed at one end with a finger hold 37. This frame when moved upwardly by the finger hold 37 will engage the shorter end of catch 23, hold the same in elevated position, and allow the plate 14 to be raised to operative position without stop- 110

ping the oscillator 29. In other words, this upward movement of the plate by means of the frame 36, first swings the catch 23 out of the path of the oscillator 29, and when the 5 plate is elevated and the cord in operative position with relation to the wire frame 24, the catch will be held in this position.

A toothed bar 38 is connected to bell-crank-lever 8, and extends through a slot 10 39 in a bracket 40 on one of the posts 15. The teeth of this bar 38 engage the lower wall of the slot 39, so that when the plate 14 falls, bar 38 will be drawn forwardly and 15 elevate the cone 5 out of engagement with roll 4, thereby stopping the turning of the cone. The teeth of bar 38 are inclined or ratchet shaped, so that as the cone increases 20 in diameter, this bar may be moved rearwardly tooth by tooth so that the cone will 25 be elevated regardless of its diameter in the event the thread breaks.

The relatively long arm 20 supports at its free end a short rod 41 on which a table 42 is secured. This table 42 at its outer 25 edge has a guide 43 through which the cord 17 is drawn, and on the table a rotary weight 44 is mounted on a vertical post 45 and bears upon the cord to act as a tension device. Between the table 42 and the wire 30 frame 24, the cord passes through my improved slub catcher, which consists of two brushes 46 facing each other and supported in holders 47 fixed to the ends of a lazy tongs 48. This lazy tongs 48 comprises 35 four links as clearly shown in Fig. 2 pivotally connected as shown, and one pivotal connection at the lower end of the lazy tongs consists of a bent rod 49 which is rigidly secured to the frame bar 1, and acts as a 40 stationary pivot for the lazy tongs. The upper pivot 48^a of the lazy tongs comprises a screw which is secured to arm 25^a on bracket 25, so that when the plate 14 moves 45 downwardly, the lazy tongs operates to separate the brushes as clearly shown.

The brushes each consist of a backing plate 50 preferably of fabric through which a large number of wires 51 project, forming an extended wire surface. The backing 50 plates 50 are adapted to be slid into and out of the holders 47, so that the brushes may be readily replaced when worn or broken.

When the plate 14 is elevated to operative 55 position, the lazy tongs 48 will bring the brushes together, engaging the thread 17 with the teeth of the brushes located side by side, that is, the teeth of one brush will project between the teeth of the other brush, and form a circuitous passage for 60 the thread and insure the catching of any slub or lump of the thread. In other words, the brushes absolutely insure a clean smooth 65 thread to the cone, and if the slub, lump, or knot is so fixed to the thread that it will 70 not pass through the brushes, the thread

will be broken and the parts moved downwardly as above explained, elevating the cone 5 and stopping the operation of winding until the thread is repaired, and the parts moved back into normal position.

It will thus be seen that with my improved slub catcher, the dropping of the plate of the frame due to the breaking of the cord, will cause the brushes to separate and when the parts are moved back to normal position, the brushes will come together on opposite sides of the cord, so that the operation of the slub catcher is automatic with the operation of the other parts of the apparatus.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A slub catcher adapted for use in a winding machine comprising two brushes, means supporting the brushes and arranged to hold said brushes together and compel a thread to pass between them, and means co-operating with the supporting means for separating the brushes when the winding machine is stopped, substantially as described.

2. A slub catcher adapted for use in a winding machine comprising two brushes, each brush consisting of a fabric backing and a plurality of wires projecting from the surface thereof, and means normally holding said brushes together at opposite sides of a thread with the wires of one brush projecting between the wires of the other brush, and means for separating the brushes when the winding machine is stopped, substantially as described.

3. A slub catcher adapted for use in a winding machine comprising two brushes, lazy tongs supporting at their free ends the said brushes, and means co-operating with the lazy tongs for separating the brushes when the winding machine is stopped, substantially as described.

4. A slub catcher adapted for use in a winding machine comprising two supporting members, brushes carried by said members and movable thereby into position at opposite sides of the thread, and means for moving the supporting members to separate the brushes when the winding machine is stopped, substantially as described.

5. A slub catcher adapted for use in a winding machine comprising two brushes, each brush consisting of a backing plate having a plurality of teeth projecting from

the plate, the teeth of one brush adapted to be projected between the teeth of the other brush, holders removably supporting said brushes, and lazy tongs secured to said holders, and means for moving the holders to separate the brushes when the winding machine is stopped, substantially as described.

6. A stub catcher adapted for use in a winding machine comprising lazy tongs arranged to be connected at one end to a fixed part of a winding machine, brushes carried by the free end of the lazy tongs and

adapted to normally engage the opposite sides of a thread, and means engaging the lazy tongs between the ends of the latter, said means arranged to separate the brushes when the winding machine is stopped, substantially as described.

In testimony whereof I have signed my name to this specification in the presence of two subscribing witnesses.

MOSES EWING.
